US00D731545S

(12) United States Design Patent
Lim et al.

(10) Patent No.: US D731,545 S
(45) Date of Patent:  Jun. 9, 2015

(54) DISPLAY SCREEN OR PORTION THEREOF
WITH ICON

(71) Applicant: Samsung Electronics Co., Ltd., Suwon-si (KR)

(72) Inventors: Eun-Sil Lim, Seoul (KR); Hae-Mi Yoon, Seoul (KR)

(73) Assignee: Samsung Electronics Co., Ltd., Suwon-si (KR)

() Term: 14 Years

(21) Appl. No.: 29/456,176

(22) Filed: May 29, 2013

(30) Foreign Application Priority Data

Mar. 12, 2013 (KR) 30-2013-0012443

(51) LOC (10) Cl. 14-04

(52) U.S. Cl.

USPC D14/492

(58) Field of Classification Search

USPC D14/485-495; 715/703, 715, 727, 763, 715/773, 776, 779, 839, 810, 811, 812, 813, 715/814, 815, 821, 825, 828, 833, 835, 836, 715/837, 838, 840, 846, 847, 864, 963, 974, 715/976, 977

CPC G06F 3/0482; G06F 8/34; G06F 3/04817; G06F 3/048
